UNITED STATES PATENT OFFICE.

MELVILLE CLARK, OF CHICAGO, ILLINOIS.

DISAPPEARING PEDAL FOR AUTOMATIC PIANOS.

No. 821,460.

Specification of Letters Patent.

Patented May 22, 1906.

Application filed November 10, 1905. Serial No. 286,645.

To all whom it may concern:

Be it known that I, MELVILLE CLARK, a citizen of the United States, residing at Chicago, in the county of Cook and State of Illinois, have invented new and useful Improvements in Disappearing Pedals for Automatic Pianos, of which the following is a specification, reference being had to the accompanying drawings, forming a part thereof:

10 The purpose of this invention is to provide an improved pumper-pedal mechanism for operating the bellows of the automatic playing devices in an automatic piano adapted to be moved back out of operative position and 5 substantially concealed when not in use.

It consists of the features of construction which are set out in the claims.

In the drawings, Figure 1 is a fore-and-aft vertical section through the pedal devices 20 and so much of the case as necessary to show the relation of said devices thereto. Fig. 2 is a detail fore-and-aft section of the lower part of the case in the same plane as Fig. 1, showing the pedals in the position occupied 25 when out of use. Fig. 3 is a detail front elevation showing the pedal-connecting rods folded up out of operative position. Fig. 4 is a plan view of the pedals and pedal-frame. Fig. 5 is a detail section, on an enlarged scale, 30 at the line 5 5 on Fig. 2.

In the drawings a usual construction of upright piano-case is represented comprising front board 1 and bottom board 2, which is sustained at a distance of from two to three 35 inches above the floor by casters 3. Rails 4 4, forming parallel slideways, extend fore and aft on the under side of the bottom board, being preferably bolted thereto and spaced therefrom by suitable blocks or hangers 6 6 and the check-rail 19 hereinafter mentioned. These rails serve as a supporting-track for a three-sided pedal-frame 7, which consists of fore-and-aft parallel side bars 7^a, extending from opposite ends of the front bar or intermediate side of the frame, and on this forward or intermediate side bar pedals 8 are pivoted at their heels for vertical oscillation at their forward end. The side bars 7^a of the frame 7 are preferably connected by a rod 7^d, which extends under the toe ends of the pedals and serves as a stop for the downward movement of the latter, suitable rubber bumpers 9 9 being provided to deaden the sound of the contact of the pedals with the rod. In the construction 55 shown 10 represents the receiver or main exhaust-bellows, the pumpers 11 11 being located

above the foundation-board 12, below which said receiver is mounted. The pumpers are operated in this particular construction by a lever-arm 13 at the rear end of a fore-and-aft 60 extending rock-shaft 14, which has at its forward end a second lever-arm 15. The pedals are connected with the respective lever-arms 15 by connecting-rods 16. Each of these rods has at the lower end an eye 16^a, which is 65 large enough at the upper part to pass over the head of a screw 17, set into the outer edge of a pedal, the lower part of the eye being of suitable size to pivot on the body of the screw and not permit escape over the head. 70 The upper end of the rod is provided with an adjustable eye 18, having a stem 18^a, which is hollow and interiorly threaded and of sufficient length to permit an adequate range of adjustment for modifying the operative 75 length of the connecting-rod by screwing the eye more or less onto the upper end of the rod, which is threaded for that purpose. The eye 18 engages the hooked end of the lever-arm 15 for operating the pumper. The 80 frame 7 is adapted to be lodged upon the slideways 4 4, and the said slideways are suspended at a sufficient distance below the under side of the bottom board to afford room for said frame and the pedals thereon, so that 85 the entire structure, except the detachable connecting-rods 16, may slide back under the bottom board and be concealed from sight.

At the rear end of each of the side bars 7^a of the frame 7 a pin 7^b projects outwardly 90 for engaging under a check-rail 19, which may conveniently be secured by the same bolts which carry the slideway-rails 4 4. This check-rail is provided with a stop 19^a at the rear end to limit the inward or rearward 95 movement of the pedal-frame and pedals, and it has also a similar stop 19^b in the path of the pin for limiting the outward or forward movement when the pedals are withdrawn into operative position. From a 100 point below and a little rearward of the stop 19^b the slideway-rail 6 is cut away to give its upper surface a slight slope corresponding to the inclination of the pedal-frame when its heel rests upon the floor, thus causing or permitting said frame to fulcrum on the slideway-rails at the angle where the slope commences.

A convenient method for preventing the pedal-frame from being forced backward or 110 inward by the use of the pedals is shown in Fig. 1, in which are shown the slideway-rails

4 4, extended sufficiently forward of the stop 19^b, so that the pedal-frame fulcruming over them to reach the floor at the heel causes the pins 7^b to be carried upward into a notch 19^c, 5 formed in the check-rail 19 at this point for that purpose, thus preventing any rearward movement so long as the heel of the pedal-frame remains on the floor; but by lifting the pedal-frame to horizontal position, the pin 10 clears this notch and the rearward movement, as described, can be made. When for any reason this mode of locking the pedal-frame at operative position is not regarded as sufficiently positive or reliable, use may be 15 made of a more positive lock, which consists of a rocking bolt or catch 23, mounted on each of the side bars 7^a of the frame 7, having a nose or engaging terminal 23^a, adapted to be rocked in front of the end of the check- 20 rail 19.

The rods 16 when detached from the pedals may be swung up outwardly and lodged in the felt-lined forks 24, (of which one is shown mounted on the under side of 25 the key-table 25.)

I claim—

1. In combination with the bottom board of a piano-case, a pumper-pedal frame and pumper-pedals mounted thereon adapted to 30 pass under the bottom board, and slide-bars for such frame supported on the under side of the bottom board.

2. In combination with a piano-case, parallel, substantially horizontal slideways extending fore and aft at the lower part of the case, the pedal-frame supported and adapted to slide on said slideways; pedals mounted on such frame and pumper-operating connections detachably connected to the pedals. 35

3. In combination with a piano-case, substantially horizontal fore-and-aft slideways at the lower part of the case; a pedal-frame mounted for sliding on said slideways adapted to be drawn thereon forward of the front 40 board; pedals mounted on such frame and

pumper-operating connecting-rods detachably connected at one end to the pedals respectively, and the pumper-operating levers to which the other ends of said rods are connected forward of the front board. 50

4. In combination with a piano-case, substantially horizontal fore-and-aft parallel slideways mounted on the case at the lower part; a pedal-frame adapted to be supported and to slide on said slideways, said frame 55 having outwardly-extending stop-pins at the rear end; check-bars extending above the slideways respectively parallel thereto, overhanging the path of the stop-pins; stops at the forward ends of said check-bars in the 60 path of the pins, the slideways being cut away at the forward ends to permit the pedal-frame to fulcrum thereon for swinging downward when the stop-pins reach the stops. 65

5. In combination with a piano-case, parallel fore-and-aft slideways suspended from the under side of the bottom board; a pedal-frame mounted for sliding on such slideways and pedals thereon, said frame and pedals 70 being adapted to pass entirely under the bottom board in such sliding.

6. In combination with a piano-case having a bottom board, means for supporting the same to hold the bottom board slightly 75 elevated from the floor; horizontal fore-and-aft slideways mounted on the under side of the bottom board; a pedal-frame and pedals thereon adapted to pass under the bottom board, said frame running on said slideways, 80 and detachable pumper-operating connections at the forward side of the front board.

In testimony whereof I have hereunto set my hand, in the presence of two witnesses, at Chicago, Illinois, this 7th day of November, 1905. 85

MELVILLE CLARK.
